(57) **CLAIM**

The ornamental design for a lip balm as shown and described.

DESCRIPTION

FIG. 1 is a perspective view of a lip balm showing my new design;

FIG. 2 is a front view thereof;

FIG. 3 is a rear view thereof;

FIG. 4 is a left side view thereof;

FIG. 5 is a right side view thereof;

FIG. 6 is an enlarged top plan view of the lip balm of FIG. 1; and,

FIG. 7 is an enlarged bottom plan view of the lip balm of FIG. 1.

The broken lines in the figures illustrate portions of the lip balm that form no part of the claimed design.

1 Claim, 6 Drawing Sheets
